COMBINATION BRASSIÈRE AND FOUNDATION GARMENT

Minna R. Schubert, Saginaw, Mich., assignor to
Le Monde Corset Company, Saginaw, Mich., a
corporation of Michigan

Application February 4, 1939, Serial No. 254,646.

2 Claims. (Cl. 2—30)

This invention relates to foundation garments such as girdles or corsets and has for its object the provision of an improved garment having overlapping bands or wings permanently secured to or made integral with the girdle or corset to support the upper abdomen and conceal the top line of the girdle, and in which the said wings may be diagonally tensioned for this purpose without stressing an attached brassière or otherwise undesirably flattening the breasts. More particularly, it relates to a one-piece garment including a brassière permanently or detachably secured to the girdle and to the abdomen-supported wings referred to.

Garments of this kind hitherto offered have been so made that the necessary tension upon the overlapping abdominal wings has been exerted laterally downward upon the fabric of the brassière, pulling diagonally downward across the breasts. For this reason perhaps this intrinsically convenient and desirable type of garment has not previously been successfully marketed.

My improvement for the first time makes available a foundation garment of this general kind in which the diagonally-directed downward tension of the diaphragm-restraining members or wings is divided and transmitted laterally below the breasts to the sides of the garment and vertically to a top band of the garment above the breasts so that the body fabric of the brassière is not stressed and the undesirable flattening effect of earlier garments of this kind is avoided. Thus a unitary foundation garment is provided affording the natural youthful lines demanded by the trade today and providing the desirable overlapping wings covering the top and front of the girdle which serve both to conceal the top line of the girdle and to lift, flatten, and confine the flesh over the diaphragm.

Referring to the drawing, Fig. 1 shows in front view, a garment according to the invention fastened upon a wearer;

Fig. 2 is a fragmentary view of the garment of Fig. 1 partly open additionally to show its construction; and

Fig. 3 is a fragmentary front view of an alternative form of garment embodying the invention.

The garment of Figs. 1 and 2 consists of a girdle having a front-opening brassière consisting of halves 2 and 3 made as integral parts of the garment. The brassière halves 2 and 3 are secured along their rearward edges to the sides of the garment. In the garment shown, they are

sewn to the forward edges of the back of the girdle, which is higher than the front. Downwardly tapered wings 4, 5 are secured at their upper edges to the lower margin of the brassière halves 2 and 3 respectively, and at their rearward upright edges 6 and 7 are fixed to the sides of the girdle in the instant garment along continuations of the seams by which the halves 2, 3 of the brassière are sewn to the girdle. The diagonal bands or wings 4, 5 are so shaped and proportioned that they extend past the front midline of the garment, overlapping and covering the top edge of the girdle 1. They may be made of elastic webbing, or provided as shown with elastic extensions, and have at their lower ends suitable fasteners for securing them to the body of the corset so that they may exert a yielding tension over the upper abdomen. In the garment shown buttons are provided at the ends of the wings 4, 5, which selectively or adjustably fasten into a plurality of buttonholes provided in tabs 8, 9 fixed to the sides of the girdle, or other fastening means may of course be employed if desired. When the garment is fitted the tension upon wings 4, 5 is adjusted and determined so that each exerts the necessary downward transverse pull to produce the desired restraining pressure upon the wearer's flesh above the top of the girdle. In the garments heretofore constructed along the foregoing general lines, the tension of the overlapping wings as 4, 5 was applied diagonally across the breasts, thus producing an undesirable flattening effect. Especially with the present-day uplift brassière this earlier construction was entirely impractical, and necessarily therefore foundation garments have been made and sold without the diagonally-tensioned overlapping wings for covering the top line of the girdle.

The specific improvement constituting the present invention consists of a novel construction of the brassière top to which the wings 4 and 5 are fixed. The tailored and formed body of the brassière 2, 3 is made of the customary lace or other light fabric. At the center of the halves a vertical inelastic tape 11 is fixed to, or made integral with the front lateral edges of the wings 4 and 5 at the center of the brassière. In Figs. 1 and 2 this inelastic tension member consists of two tapes 11 along the adjacent front edges of the halves 2, 3, which continue down the front edges of wings or bands 4 and 5. Hooks or other hook-and-eye fastening means for fastening the halves 2, 3 may conveniently also be anchored to tapes 11.

The tape or tapes 11 are fixed at their upper ends to an inelastic tape or band 12 at the top of the garment, to which the upper edge of the brassière may also be sewn or detachably fastened. The top band 12 is secured at its ends to the upper lateral edges of the back panel of the girdle which lie at the sides of the wearer. It may be provided with shoulder straps 13, as shown, or it may be tailored to the wearer and made self-supporting in garments designed for wear with strapless evening gowns. In either case it is fitted and arranged so as to support all downward pull of wings 4, 5 upon tapes 11.

It will be seen by reference to Fig. 1 that the diagonal tension exerted downwardly by each wing 4, 5 is, by suitable roaching or pre-tensioning of the central upright edges of the wings and the brassière halves divided into substantially vertical and horizontal components. The arrows in Fig. 1 diagrammatically show the tension on wings 4 and 5 translated into horizontal pull along the lower edges of the wings to their points of fastening 6 and 7 to the sides of the girdle 1 and into downward pull along their substantially vertical forward edges. The vertical pull is carried by the inelastic tapes 11 to the similarly inelastic top binding 12 above the wearer's bust, whence it may be carried by the shoulder straps 13. All tension transmitted to the brassière members is thus carried by the binding or tapes 11 and 12, there being no tension or pressure whatever applied to the formed fabric of the brassière proper. Should, however, the band 12 yield or sag slightly under the pull of wings 4 and 5, the fabric of the brassière will be loosened, rather than tightened.

Referring to the alternative construction shown in Fig. 3, the general construction and functioning of the garment is identical with that of the garment shown in Figs. 1 and 2. The garment differs in detail in that a one-piece brassière 2a

is used, and one wing 5a is detachably fastened by hooks or fasteners 14 along the lateral edge 7a of the girdle 1, together with one edge of the brassière. A single inelastic tape 11a is provided at the mid-line, secured at its lower ends to wings 4a, 5a, and at its upper end to the top band 12. Here, as in the garment of Figs. 1 and 2, the tape 11a is preferably stretched tight if it is sewn to the brassière, while the fabric of the brassière is loosened or gathered slightly. Thus tension upon it will not affect the position of the brassière.

While I have shown and described a preferred form of the invention, it is within the scope of the present invention to make the brassière detachable from or separate from the strain-supporting members 11 and 12.

Having thus described my invention, what I claim and desire to secure by Letters Patent is:

1. A foundation garment comprising a girdle, a pair of wings secured one at each side of the girdle, arranged to overlap and be detachably fastened to the girdle on opposite sides of its mid-line, said wings shaped and positioned when fastened to overlie the upper edge of the top of the girdle and be tensioned laterally and downward to restrain the flesh of the wearer thereabove, their upper edges lying below the breasts of the wearer, an inelastic band adapted to resist downward tension, connecting and secured at its ends to the opposite upper sides of the girdle, and positioned and formed to lie above the breasts of the wearer, and a narrow substantially vertical inelastic tension-sustaining member connecting said band and the upper edges of said wings at or adjacent the front center line of said garment.

2. A garment as claimed in claim 1, having a brassière secured at its top to said inelastic band, at its sides to the sides of said girdle, and at its bottom to the top edges of said wings.
